(57) CLAIM

The ornamental design for a table flame heater, as shown and described.

DESCRIPTION

FIG. 1 is a front side view of a table flame heater showing my new design;

FIG. 2 is a rear side view thereof;

FIG. 3 is a left side view thereof;

FIG. 4 is a right side view thereof; and,

FIG. 5 is a top plan view thereof.

A bottom view is omitted because it is plain and unornamental and forms no part of the subject matter of the claimed design.

In the drawings, the broken lines depict unclaimed subject matter only and form no part of the claimed design.
